UNITED STATES PATENT OFFICE.

WILLIAM A. BOND, OF LYNNFIELD, MASSACHUSETTS, ASSIGNOR TO UNITED SHOE MACHINERY COMPANY, OF PATERSON, NEW JERSEY, A CORPORATION OF NEW JERSEY.

LASTING-MACHINE.

No. 867,469.

Specification of Letters Patent.

Patented Oct. 1, 1907.

Application filed February 23, 1906. Serial No. 302,484.

To all whom it may concern:

Be it known that I, WILLIAM A. BOND, a citizen of the United States, residing at Lynnfield, in the county of Essex and Commonwealth of Massachusetts, have 5 invented certain Improvements in Lasting-Machines, of which the following description, in connection with the accompanying drawings, is a specification, like reference characters on the drawings indicating like parts in the several figures.

10 This invention relates to that type of lasting machines known as the "Hand method lasting machine", an example of which is shown in United States Letters Patent No. 584,744, granted June 15, 1897. As is fully explained in that patent, this type of machine 15 comprises a single pair of grippers for engaging a small portion of the upper at a time and manipulating it into lasted position, where it is secured before the next operation of the machine.

10 The lasting operation as a whole is carried out progressively by repeated operations of the machine on different portions of the upper. Actuating mechanism is provided for moving the grippers into position to engage the upper, closing them, lifting them to stretch or updraw the upper, and moving them over 25 the last bottom and downwardly to overdraw the upper and place it in position to be secured by the tacks or other fastening means employed for holding the upper to the innersole, and finally for releasing the upper. Normally the grippers move up and down and forth 30 and back in their central position in alinement with the median line of the machine, or in a path parallel with the median line of the machine. When lasting the toe portion of the upper of a shoe, however, and sometimes other portions, it is necessary to plait or 35 crimp the upper for laying smoothly the surplus stock.

For this purpose the grippers are moved laterally to one side of the median line of the machine to position them for gripping the upper, and after they have been closed upon the upper they are moved laterally in the 40 reverse direction to the other side of the median line of the machine for plaiting the upper before it is secured in place. Preferably also the grippers are turned during their lateral movement whereby the portion of upper being plaited is twisted, because by 45 so doing a smoother and more satisfactory plaiting or folding of the surplus upper material is obtained.

The lateral movement of the grippers to one side of the median line of the machine into position for gripping the upper and then in the reverse direction 50 toward the other side of the median line is automatically affected in the regular operation of the machine by mechanism comprising, as herein shown, a yielding element. In practice the yielding element is compressed or put under tension by the resistance of the

upper material during the movement of the grippers 55 for plaiting the upper, and when the grippers are opened to release the upper the reaction of the yielding element moves the grippers laterally beyond the position to which they were intended to be moved. The amount of this excessive movement varies according 60 to the extent to which the yielding element has been compressed during the plaiting of the upper, and sometimes, as when the upper being lasted is heavy or inelastic, the grippers are thus moved laterally with such violence as to break the grippers mechanism or 65 otherwise injure the machine. It will be understood that in the operation of the machine the grippers are moved rapidly, it being customary to run the machine at the rate of about 150 cycles per minute, and it is sometimes found that the inertia of the grippers causes 70 them to move laterally farther than they are intended to do on their return to gripping position. The grippers thus frequently grip the upper at different distances from the median line of the machine so that the plaits formed are not so even as is desirable. This 75 difficulty is particularly liable to occur at times when the reaction of the yielding element increases the lateral throw of the grippers in the direction of their plaiting movement, as described above.

Heretofore the lateral movement which the actuating mechanism has been arranged to impart to the grippers has been uniform or substantially uniform in extent on each side of the median line, the grippers moving approximately as far beyond the median line of the machine in one direction for placing the upper as they 80 moved beyond the median line in the other direction for gripping the upper. I have discovered, however, that in lasting Goodyear or welt shoes the smoothest and most perfect fitting of the upper to the last is obtained and better plaiting of the overdrawn upper is secured 85 by moving the grippers laterally from a gripping position at one side of the machine to a point at or near the median line of the machine. By thus stopping the lateral movement at or near the median line of the machine the final drawing of the upper into lasted position is effected by a strain substantially at right angles to the edge of the last. In lasting Goodyear shoes I prefer to continue the turning movement of the grippers after the lateral movement has been arrested. 90 This continued turning of the grippers twists the portion of upper held by them and tightens it at the edge remote from the previously lasted portion of upper just before it is fastened to the innersole of the shoe.

For the purpose of overcoming the difficulties which have been mentioned and of securing the proper movements of the grippers for lasting Goodyear shoes I have provided means for regulating the lateral movement of the grippers.

To this end a feature of my invention consists in providing means for limiting the lateral movement of the grippers in the direction for forming the plait and placing the upper in overworked position. As herein shown, said limiting means is arranged for adjustment to vary the extent of the lateral movement which may be given to the grippers in accordance with the different conditions encountered in the use of the machine. Thus the limiting means may be employed for preventing excessive lateral movement of the grippers, after they have released the upper, whether it is caused by the reaction of the yielding element if a yielding element is used, or by the inertia of the rapidly moving mechanism or any other cause. The limiting means may also be employed for stopping the lateral movement of the grippers at any desired point with relation to the median line of the machine independently of the normal length of stroke of the yielding actuating mechanism. The limiting means will preferably be arranged to arrest the lateral movement of the grippers while the turning movement is continued, whereby the portion of upper held by the grippers is given a final twist before it is secured in lasted position.

One of the advantages of the invention when the limiting means is used in combination with actuating mechanism comprising a yielding element is that the tension of said yielding element may be made sufficient, if desired, to insure the lateral movement of the grippers to the desired position at each operation of the machine, the limiting means always stopping said lateral movement at the same point so that perfect uniformity in the plaits of the upper may be secured. By this means also the strain applied to the upper for pulling it laterally may be accurately regulated as the limiting means arrests the pull on the upper, thus preventing an increase of strain during the completion of the stroke of the actuating mechanism. Preferably also limiting means is provided for regulating the extent of lateral movement of the grippers toward gripping position whereby overthrow of the grippers in this direction, produced by their inertia or by any other cause, is prevented and the grippers always are closed upon the stock at the same point with relation to the median line of the machine. These and other features of the invention, including certain details of construction and combinations of parts, will be hereinafter described and will be pointed out in the claims at the end of the description.

Figure 1 is a front elevation of the upper portion of a lasting machine equipped with the present invention and adjusted for plaiting the shoe upper, the grippers being shown in position for gripping the stock. Fig. 2 is a detail view of the mechanism for laterally moving and turning the grippers, the grippers being shown in full lines in the position occupied by them when the plait has been formed and before the stock is released in lasting a McKay shoe. The dotted line shows the further position to which the grippers tend to move because of the reaction of the spring through which they are actuated laterally. Fig. 3 is a view similar to Fig. 2 and shows the position of the grippers when the plait has been formed while operating upon a Goodyear shoe in which the overworked upper is secured in position by a wire binder. Figs. 4 and 5 are diagrammatic views illustrating approximately the

paths followed by the grippers in their lateral and turned movement while lasting McKay and Goodyear shoes respectively. Fig. 6 is a perspective view of the grippers operating mechanism.

In the construction of lasting machine herein shown to which the present invention has been applied the grippers, comprising members 14 and 16 adapted for relative movement to grip and release the stock, are mounted upon shanks or bars 13 and 15, the bar 13 being tubular and receiving the bar 15, which is movable longitudinally with relation thereto for closing and opening the grippers. The bar 13 is provided on its upper end with a spherical head 17, which is secured to the front end of the lever 18, by means of which the grippers are moved up and down, said lever 18 being pivoted at 19 and connected through a plate E with a cam 280 on the shaft D. The grippers are guided in their vertical movements through a passage in the rear side of a carrier 30, formed at its lower end as a horizontal sleeve 22; the end portions of which are received in bearings 31 formed on the front end of a bar which is arranged to be actuated for moving the grippers toward the head of the machine into position for gripping the portion of the upper being lasted and away from the head of the machine for overdrawing the upper. In the upper end of the carrier 30 is formed a boss 47 which receives the screw-threaded tubular nut 48. Mounted in the nut 48 is a spindle 44, the lower end of which rests on a bar or lever 43, which is normally supported at its opposite ends by studs 41 and 42 on the carrier. The spindle 44 is pressed downwardly by a spring 49 confined within the tubular nut 48 and acting on a collar formed on the spindle near its lower end. The pressure of the spindle upon the bar 43 may be regulated by adjusting the nut in the lug 47. Centrally arranged below the bar 43 is a fulcrum pin 46, upon which is mounted a triangular lever 45, the upper arms of the lever bearing normally against the lower face of the bar 43. The lower arm of the triangular lever has pivotal connection at 52 with a slide 51 mounted for longitudinal movement in the sleeve 22. It will now be understood that the pressure of the spring 49 will normally hold the bar 43, the triangular lever 45, and the slide 51 in the position shown in Fig. 1, the pivotal connection 52 between the triangular lever and the slide being in alinement with the gripper bar 13. A movement of the slide 51 longitudinally in one direction will be transmitted through the pivotal connection 52, triangular lever 45, bar 43, and spring 49 to the carrier 30 for yieldingly moving the grippers laterally toward one side of the median line of the machine. A movement of the slide 51 in the reverse direction will similarly be transmitted to the carrier 30 for moving the grippers toward the other side of the median line of the machine. As herein shown, the slide 51 is actuated for moving the grippers laterally by a segment-shaped block 63 adjustably mounted in a suitably actuated crank arm 57, the movement being transmitted to the slide through links X⁸ and 55, the latter of which is connected to the slide by a universal joint.

The link X⁸ above mentioned has connection with a lever X⁶, which is fulcrumed at X⁹ to the machine frame. The upper end of this lever is connected by a link X⁷ to a rack bar X³ longitudinally movable in a

guideway formed for it in the front end of the lever 18. The rack bar engages teeth formed on the spherical head 17 of the gripper bar 13. By means of this connection the gripper bar 13 is rotated for turning the grippers simultaneously with the operation of the actuating mechanism described for laterally moving them. The machine as thus far described is sufficiently illustrated in Figs. 1, 2 and 6 and it is or may be substantially the same as shown and described at length in the 10 Letters Patent above referred to, although the connection between the lever X^6 and the link X^7 may be a yielding connection, as shown in Fig. 2, on machines used for certain classes of work.

It will be understood that the lateral movement of the grippers is yieldingly effected in both directions because this movement is transmitted to the grippers through the spring 49. In the operation of lasting the toe portion of McKay shoes the grippers are moved laterally to one side of their central position, which usually is in the median line of the machine and is so designated herein, into gripping position and they are closed by a downward movement of the bar 15 effected through the lever 28 actuated by cam 40 on the shaft D as shown in Fig. 6. The grippers are then lifted for 25 updrawing the upper and moved away from the machine head for overdrawing the upper. After these latter movements have been partially or completely effected the grippers are laterally moved and turned from the lateral and angular position shown in Fig. 1 across 30 the median line of the machine to the position shown in Fig. 2 for plaiting the upper. This lateral movement is, it will be understood, effected yieldingly through the spring 49, and if as is usual the amplitude of the lateral movement which the actuating mechanism 35 is arranged to produce is greater than the elasticity of the stock will permit the grippers to have, the triangular lever 45 will turn upon the carrier 30 against the pressure of the spring 49, the parts thus assuming such relative positions as are shown in full lines in Fig. 2, 40 supposing that the lateral, plaiting movement proceeds from left to right. As soon as the grippers have been opened to release the upper, which occurs when the head of the lever 28 is rocked upwardly with relation to the lever 18, the resistance to the completion of the 45 lateral movement of the grippers is withdrawn and the compressed spring 49 causes this movement to be completed. The force exerted by the spring in thus moving the grippers is sufficient, in case the tension of the spring is considerable, to force the grippers past the 50 normal limit of their lateral movement. It not infrequently happens that in this excessive movement of the grippers the bar 13 strikes an adjacent portion of the machine, as, for example, the bracket X in Fig. 1, thus sometimes injuring and even causing breakage of 55 parts. This difficulty is overcome in accordance with this invention by providing means for limiting the lateral movement of the grippers. As herein shown, this means comprises a collar 25 mounted upon the sleeve 22 in position to engage one of the bearings 31 in which 60 the sleeve slides when the grippers are moved laterally. The collar is preferably adjustable upon the sleeve, and as herein shown is formed as a band having screw-threaded engagement with the sleeve and provided with a binding screw 27 for locking it in adjusted 65 position on the sleeve. By properly adjusting the lim-

iting means the lateral movement of the grippers can be stopped in any desired position—as, for example, at the limit of their normal lateral stroke thus preventing the excessive movement due to the reaction of the spring 49. In lasting McKay shoes it is the custom to 70 begin the plaiting of the upper at the center of the toe and plait that side of the toe portion of the shoe and then, commencing again at the center, to plait the opposite side of the toe of the shoe. In Figs. 1 and 2 the machine is shown as plaiting from the center of the toe 75 toward the left-hand side and the means, 25, for limiting the excessive lateral movement or overthrow of the grippers is located on the outer end of the sleeve 22 and arranged to engage with the outer side of the adjacent bearing 31. For limiting the movement when the 80 plaiting is done by reverse movements of the grippers a second collar 26 is applied to the sleeve 22 in position to engage the inner side of the bearing 31. The machine is operated rapidly, the grippers usually moving at the rate of about 150 reciprocations per minute, and 85 their inertia sometimes causes them to go too far as they move laterally toward gripping position. This causes the grippers to engage the upper at different distances from the median line of the machine and produces irregular plaiting of the upper. By means of the 90 two collars 25 and 26 the lateral movement in each direction is positively limited so that there is no danger of the grippers closing upon the stock in the wrong position, or of the reaction of the spring 49 throwing them so far laterally as to engage the adjacent parts of the 95 machine.

In the operation of lasting Goodyear shoes it is the present practice to use a binder of wire or other continuous material instead of tacks for securing the toe portion of the upper in overworked position. The free end of the wire is secured to a tack at one side of the shoe and drawn under tension from a reel and presses and holds the successively overworked portions of upper into the angle of union between the feather edge and shoulder of the innersole as the lasting proceeds. 100 I have found that, when the grippers are permitted to move laterally for plaiting the upper as far toward one side of the machine as it is desired for them to move toward the other side for gripping the upper, wrinkles are liable to be formed in the upper at the edge of the 110 last, and I have discovered that this difficulty may be avoided by stopping the lateral movement of the grippers at or about the median line of the machine so that the strain for finally overlaying the upper upon the innersole is approximately at right angles to the edge 115 of the last. For accomplishing this end I preferably adjust the limiting means 25 upon the sleeve 22 of a welt lasting machine so that it will arrest the lateral movement of the grippers in the direction for plaiting the upper at approximately the time the grippers reach 120 the median line of the machine. The stop may of course be adjusted to arrest the lateral movement of the grippers at any desired point and the tension of the spring 49 may be so regulated as to insure that the grippers always will be moved to such desired 125 point for forming regular plaits in the upper. It is to be noted that the limiting means not only regulates the lateral movement of the grippers, but also limits the lateral pulling strain which will be applied to the 130 stock because the pulling strain is arrested when the

limiting means arrests the movement of the grippers and does not go on increasing while the actuating mechanism completes its stroke. By properly adjusting the two stops 25 and 26 the extent of movement of the grippers on one side of the median line of the machine as compared with the movement on the other side can be regulated as desired. I prefer to permit the turning movement of the grippers to continue after their lateral movement has been arrested, whereby the upper is given a final twisting movement with the grippers substantially at the median line of the machine. This final twisting of the portion of upper held by the grippers just before it is secured by the binding wire lays the plait over upon the plait last formed and also tightens it at the edge adjacent to the unlasted part of the upper by pulling it snugly over the edge of the last. It is found in practice that that edge of the plait adjacent the unlasted portion of the upper tends to slip back slightly after the plait is released by the grippers and the final twisting of the plait counterbalances this tendency of the upper to slip back.

It will of course be understood that the particular means or device for limiting the lateral movement of the grippers may be of any suitable form or construction and may be applied to the grippers or the grippers actuating mechanism at any desired place, the invention not being limited to the particular construction herein described for obtaining the useful results pointed out. Also it is obvious that the invention is not limited to use with the particular grippers actuating mechanism with which it is herein described as associated.

Having explained the nature of my invention and described one form of mechanism embodying the same, I claim as new and desire to secure by Letters Patent of the United States:—

1. In a machine for working an upper over a last, the combination with grippers, of actuating mechanism arranged for moving the grippers laterally to plait the upper, and means for limiting the lateral movement of the grippers.

2. In a machine for working an upper over a last, the combination with grippers, of actuating mechanism arranged for moving the grippers laterally to plait the upper, and means for limiting the lateral movement of the grippers, said means being adjustable to vary the extent of lateral movement which the grippers may have imparted to them.

3. In a machine for working an upper over a last, the combination with grippers and means for operating them to grip and release the upper, of actuating mechanism comprising a yielding element arranged to move the grippers from one side of the machine across the median line of the machine to the opposite side thereof for plaiting the upper, and means for preventing overthrow of the grippers caused by the reaction of the yielding element after the grippers have released the stock.

4. In a machine for working an upper over a last, the combination with grippers, of actuating mechanism, comprising a yielding element, arranged for moving the grippers laterally toward and from gripping position for the purpose of plaiting the upper, and means for limiting the lateral movement of the grippers in each direction.

5. In a machine for working an upper over a last, the combination with grippers, of actuating mechanism comprising a yielding element arranged to move the grippers from one side of the machine across the median line of the machine to the opposite side thereof for plaiting the upper, and means arranged to be positioned for stopping the lateral movement of the grippers approximately at the median line of the machine. 65

6. In a machine for working an upper over a last, the combination with grippers, of actuating mechanism for moving the grippers laterally and turning them, and means for varying the relative extents of said lateral and turning movements. 75

7. In a machine for working an upper over a last, the combination with grippers, of actuating mechanism for moving the grippers laterally and turning them, and means for arresting one of said movements while the other movement continues. 80

8. In a machine for working an upper over a last, the combination with grippers, of actuating mechanism for moving the grippers laterally and turning them, and means for arresting the lateral movement while the turning movement continues. 85

9. In a machine for working an upper over a last, the combination with grippers, of actuating mechanism for moving the grippers laterally to plait the upper, and means for arresting the lateral movement, said machine having provision for turning the grippers after the lateral movement has been arrested. 90

10. In a machine for working an upper over a last, the combination with grippers, of actuating mechanism therefor having a predetermined stroke, a yielding connection arranged between the actuating mechanism and the grippers and having sufficient strength to insure the movement of the grippers to a desired position, and means for preventing the movement of the grippers beyond said desired position. 95

11. In a machine for working an upper over a last, the combination with grippers, means for actuating the grippers to engage the upper and mechanism adapted to impart yieldingly to the grippers while they have hold of the stock a movement in excess of the distance it is desired to pull the stock, of means for arresting the movement of the grippers and thereby regulating the pulling strain on the stock. 100

12. In a machine for working an upper over a last, the combination with grippers, of a carrier therefor and actuating mechanism for moving the grippers laterally, said actuating mechanism comprising a slide mounted for movement with relation to said carrier, a yielding connection between the slide and the carrier, and means for limiting the movement of the grippers independently of the movement of the slide. 110

13. In a machine for working an upper over a last, the combination of grippers movable laterally to form a plait in the upper, and means to limit the lateral movement, of means for actuating the grippers to tighten the plait at its edge adjacent to the unlasted portion of upper after the lateral movement has been discontinued. 115

14. In a lasting machine, the combination with grippers and actuating mechanism therefor including means for yieldingly moving the grippers laterally to plait the upper, of means comprising co-operating relatively adjustable stop members one of which is movable with the grippers for limiting the lateral movement of the grippers. 125

In testimony whereof I have signed my name to this specification in the presence of two subscribing witnesses. 130
